Primary Examiner—Carol Rademaker(74) *Attorney, Agent, or Firm*—Wolf, Block, Schorr & Slois-Cohen(57) **CLAIM**

The ornamental design for a perfume bottle, as shown and described.

DESCRIPTION

FIG. 1 is a front, bottom, and left side perspective view of a first embodiment of a perfume bottle;

FIG. 2 is a front elevational view thereof;

FIG. 3 is a rear elevational view thereof;

FIG. 4 is a left side elevational view thereof, the right side elevational view being a mirror image;

FIG. 5 is a bottom plan view thereof;

FIG. 6 is a top plan view thereof; and,

FIG. 7 is a second embodiment of the perfume bottle of Embodiment 1, the only difference being that the triangular shaped opening is now shown in broken lines as unclaimed environment.
